UNITED STATES PATENT OFFICE.

JAMES J. BILLINGSLEY, OF KINSMAN, OHIO.

GAME.

SPECIFICATION forming part of Letters Patent No. 630,647, dated August 8, 1899.

Application filed August 5, 1898. Serial No. 687,874. (No model.)

To all whom it may concern:

Be it known that I, JAMES J. BILLINGSLEY, of Kinsman, in the county of Trumbull, State of Ohio, have invented a new and useful Improvement in Games, of which the following is a specification, reference being had to the accompanying drawings and to the letters of reference marked thereon.

This invention relates to a parlor or indoor game of skill of the class which is generally played by two players with movable pieces or men upon a checkered board in the manner of chess, checkers, or other games of like character; and it consists of a board or table of novel construction and of pieces or men, being those used in the well-known game of chess with the addition of a new and original piece for each player and having a new object in games of this class, the arrangement and moves of the pieces, and the rules of the game, as hereinafter more fully described.

In the accompanying drawings, which form a part of this specification, Figure 1 shows the plan and arrangement of the board or table, consisting of eighty-one (81) squares of nine (9) parallel rows, with nine (9) squares in each row, and checkered after the manner of a chess-board by using different colors or other distinguishing marks on alternating squares and having the new and original feature of having the middle rows of squares A to B and C to D (which cross each other at right angles in the center of the board) further distinguished by the use of a third color or other distinct mark, which lines of squares A to B and C to D, I shall call "barricade lines," the use of which I shall more fully describe hereinafter. I prefer to mark the squares of the barricade-lines with a circle within each square and use a third and distinct color in all the space within the barricade-lines and outside of the circles so drawn, as shown at A to B and C to D. The square in the center of the board common to both barricade-lines I shall call the "throne" or "kingdom."

Fig. 2 shows the pieces used in play. E is the crown prince, represented by a human head—a new and original piece and for which I prefer to name the game, it being the most important piece used in play. The remaining pieces I prefer to have in design and

name the same as those used in the well-known game of chess. F is a king, represented by a crown and scepter. G is a queen, represented by a smaller crown. H is a bishop, represented by a miter. J is a knight, represented by a horse-head. K is a rook or castle, represented by a tower. L is a pawn, represented by a small figure, as shown. The form of the pieces is immaterial, and they may be made of any suitable substance, either in disks, as shown in E, F, G, H, J, K, and L, or in standing figures, as shown in E' and J', or any other suitable form, so that the design may be preserved.

Fig. 3 shows the board or table with the pieces arranged in order ready for play. There are seventeen (17) pieces used by each player, arranged on the board as follows: On the row of squares nearest the player, on each end of the row, is placed a rook or castle, next to each rook a knight, next to each knight a bishop, and on the three (3) remaining squares a crown prince is placed in the center of the row, and next to the crown prince on the right a king and on the left a queen. In front of these, on the second row of squares from each player, are placed eight pawns, one on each square, excepting the square in front of the crown prince, as shown. The object of each player is to get his crown prince to the throne or kingdom in safety or to checkmate his opponent's crown prince, which ends the game. The moves and powers of the pieces are those used in the well-known game of chess, with the following additions and exceptions: A pawn may not move two squares on its first move. No piece may cross a barricade-line in a single move, excepting the knight, whose powers remain unchanged. On reaching the barricade-line C D a pawn may move or capture toward or on the throne-square along the barricade-line, and on reaching the throne-square or any square on the "king - row" or row nearest the opposing player a pawn may be replaced by any piece already captured from the board. A bishop in the barricade-lines may move along said lines, (rook's move,) but must remain on its own color. The crown prince may be attacked and checkmated (as a king in chess) and has the same moves and powers as the king, excepting that the king may be captured

as other pieces. Castling is not allowed; but the crown prince and the king may exchange places, when on contiguous squares, once during each game, which exchange shall constitute a move.

The advantages of this game and board with its barricade-lines, as described, over chess and the usual board used in playing (chess presenting greater similarity than any other game) are as follows: First, the range of the pieces is more limited in the game of crown prince, while they retain their peculiar moves and powers, with the slight changes necessary to adapt them to the new purpose and plan of play; second, the barricade-lines divide the board into four (4) distinct parts, in each of which the pieces are safe from immediate capture by all pieces outside of its border-lines, excepting by a knight, whose move is limited to short range; third, the new object of this game (to get the crown prince to the kingdom or throne in the center of the board) gives an unchanging objective point to be guarded and reached, while in chess the objective point moves with the king about the board; fourth, this objective point or

throne-square, being in the center of the board and touching all four (4) divisions made by the barricade-lines, is so situated that it may be guarded or reached from all parts of the board and protected by pieces under guard of the barricade-lines. Neither chess nor any other game known to me possesses these advantages.

What I claim as my invention, and desire to secure by Letters Patent, is—

A game-board composed of an equal number of playing-squares in each direction, which are alternately arranged and distinguished, the central row in each direction being distinguished from the other rows and extending from side to side across the board, and game-pieces adapted for use upon the board, substantially as specified.

In testimony whereof I have hereunto set my hand, at Kinsman, Ohio, in the presence of two subscribing witnesses.

JAMES J. BILLINGSLEY.
